DESIGN FOR A WEIGHING SCALE BEAM

Guldbrand Guldbrandsen, St. Johnsbury, Vt., assignor to Fairbanks, Morse & Co., Chicago, Ill., a corporation of Illinois

Application October 11, 1941, Serial No. 103,745

Term of patent 14 years

To all whom it may concern:

Be it known that I, Guldbrand Guldbrandsen, a citizen of the United States, residing in the town of St. Johnsbury, county of Caledonia, and State of Vermont, have invented a new, original, and ornamental Design for a Weighing Scale Beam, of which the following is a specification, reference being had to the accompanying drawing, forming a part thereof.

In the drawing:

Fig. 1 is a front elevational view of a weighing scale beam showing my new design, and

Fig. 2 is a sectional view taken on the line 2—2 of Fig. 1.

The characterizing features of my design reside in a scale beam having recessed portions therein substantially as shown.

I claim:

The ornamental design for a weighing scale beam, as shown and described.

GULDBRAND GULDBRANDSEN.
